(57) CLAIM

The ornamental design for a hands free accessory for wireless telephones, as shown and described.

DESCRIPTION

FIG. 1 is a front perspective view of a hands free accessory for wireless telephones;

FIG. 2 is a top plan view thereof;

FIG. 3 is a front view thereof;

FIG. 4 is a right side view thereof, a left side view being a mirror view thereof;

FIG. 5 is a bottom plan view thereof; and,

FIG. 6 is a rear view thereof.

The broken lines showing on the drawing disclosure are for illustrative purposes only and form no part of the claimed design.
